UNITED STATES PATENT OFFICE.

ROBERT E. BOULTON, OF SILT, COLORADO, ASSIGNOR TO SADIE J. BOULTON, OF SILT, COLORADO.

HEAD-GATE CONSTRUCTION.

Application filed March 12, 1925. Serial No. 15,028.

To all whom it may concern:

Be it known that I, ROBERT E. BOULTON, a citizen of the United States, residing at Silt, in the county of Garfield and State of Colorado, have invented certain new and useful Improvements in Head-Gate Constructions, of which the following is a specification, reference being had to the accompanying drawings.

10 This invention relates to head gate constructions and more particularly to the head gates of irrigation ditches and the like.

An important object of the invention is to provide a gate of such construction that 15 each of several parties who are being supplied from a main ditch will receive proper proportion of the water delivered to the main ditch, and this supply will not be dependent upon the maintenance of a constant 20 head or level of the main ditch.

A further object of the invention is to provide a construction of a head gate of such character that the collection of trash at the 25 mouth of the gate tending to clog the action of the gate is prevented.

A still further object of the invention is to provide means for maintaining a constant ditch size at each gate without the necessity of an expensive structure.

30 A further object of the invention is the provision of novel and improved means for adjusting the gate so that the amount of water or the proportion of water passing from the main ditch to the lateral may be 35 very finely adjusted and this adjustment secured against tampering.

These and other objects I attain by the construction shown in the accompanying drawings, wherein for the purpose of illustration is shown a preferred embodiment of 40 my invention and wherein:—

Figure 1 is a vertical sectional view through one form of head gate constructed in accordance with my invention;

45 Figure 2 is a plan view of the gate as shown in Figure 1;

Figure 3 is a front elevation of the gate;

Figure 4 is a section on the line 4—4 of Figure 3;

50 Figure 5 is a perspective of a slightly modified form of gate operating mechanism;

Figure 6 is a detailed sectional view show-

ing the adjusting mechanism and the manner of latching the same; and

55 Figure 7 is a plan view of the latching mechanism clearly disclosing the protecting shield.

Referring now more particularly to the drawings, the numeral 10 generally indicates a main ditch of an irrigating system and 11 a lateral through which water is conducted to the fields to be irrigated. From the main or supply ditch a duct 12 is led to connect the main ditch with the lateral, this duct being preferably formed of concrete. At the main ditch end of the duct the side walls of this duct have extension walls 13 and 14 coinciding with the side walls of the ditch, these extension walls and the lower edge of the duct at the main ditch end thereof being provided with an outstanding ledge 15, the upper surface of which immediately adjacent the face of the walls 13, 14 and the edge of the duct is formed 60 with a groove 16 extending entirely along the ledge and opening through both ends thereof.

65 In the construction shown in the drawings, the current in the main ditch 10 is presumed to be in the direction of the arrow A of Figure 2 and at the lower end of the downstream wall 14 a transverse baffle 17 is formed having its lower end 18 extending below the bottom of the ditch as more clearly shown in Figure 1 and its upper edge 19 at the level of the lower inner face 20 of the duct 12. This transverse baffle 17 at the far side of the ditch from the duct 12 is formed with a vertical extension 21, the outer edge 22 of which is embedded in the side wall 23 of the ditch bank and the inner edge of which projects into the ditch 10 slightly constricting the same and 70 cooperating with the wall 14 to provide a uniform size for the ditch 10 at a point immediately adjacent the duct 12. This is important due to the fact that these ditches are constantly changing in size and depth 75 due to erosion and to deposition of silt. The provision of a hard resisting surface against which the water may act to keep the surface of the ditch clean and of uniform size at the duct insures a uniform depth of the water in the ditch at each of said ducts 80 and furthermore provides points from which

an accurate estimate of the amount of water passing through the ditch at a given gate may be determined. By employing the narrow ledge 15 and its vertical extension 21, 5 the cost of the provision of such a regulating section is materially reduced.

Seated upon and secured to the upper surface of the walls 13, 14 and the upper surface of the duct 12, as at 24, is an angle bar 10 25 having the vertical flange 26 thereof downwardly directed in spaced relation to the front face of the walls 13, 14 and combining with these walls and the main ditch end of the upper wall of the duct to provide a 15 groove 27 and in opposition to the groove 16 of the ledge 15 hereinbefore mentioned. The grooves 16 and 27 receive the upper and 20 lower edges respectively of the gate 28, the gate sliding in the grooves and moving upstream of the ditch 10 to an open position. The downstream edge of the gate is provided with an out-turned curved flange 29 which acts to cause floating débris to move to the center of the stream of the ditch 10 25 instead of through the opening of the duct uncovered by the gate.

Mounted upon the upper surface of the angle bar 25 is the gate operating mechanism two forms of which are herein disclosed. Referring now more particularly to that form shown in Figures 1 to 3 inclusive, this operating mechanism includes a lever 30 pivoted to the vertical flange 26 of the angle bar and swinging in a vertical plane. The 35 upper end of this lever coacts with a segment 31 secured to the horizontal flange of the angle bar, as at 32. The segment has a plurality of arcuately arranged rows of spaced openings 32, the openings of the rows 40 being staggered with relation to one another and being fairly closely arranged. The lever 30 at that portion thereof coacting with the segment is provided with a longitudinal extending slot 33 through which is directed a 45 pin 34 having a head 35 engaging the lever at the sides of the slot and an opening 36 through which may be directed the clasp 37 of a padlock 38 or the like. The lower end of the lever has directed through a longitudinally extending slot 39 formed therein a 50 headed element 40 which engages with the door. It will be obvious that by adjusting the pin or headed element 34 to different 55 openings of the segment a very fine adjustment of the gate may be had such as is necessary to properly regulate the amount of water which is admitted to the lateral 11. It will, of course, be obvious that different arrangements of different gates upon the 60 same main ditch is necessary even though each of the users has to be supplied with the same amount of water due to the fact that each lateral from the main ditch reduces the level of the main ditch a certain amount and 65 necessitates the gates arranged further along

the main ditch in the operation of flow being opened further than at the first named ditch.

By the form shown in Figures 5, 6 and 7 an even finer adjustment of the gate may be obtained. In this form of the invention a 10 plate 41 is secured to the horizontally extending flange of the angle bar. Spaced bearings 42 are provided paralleling the vertical flange of the angle bar, these bearings being preferably carried by the plate 41 and being spaced apart a very short distance. Through these bearings a threaded shaft 43 is directed which shaft is provided with an angular arm 44 the lower end of which is engaged with the gate 28. Between the bearings 42 upon the shaft 43 a nut 45 is engaged with the shaft, the opposite side faces of this nut abutting adjacent faces of the bearings 42 so that rotation of the nut will cause longitudinal shifting of the shaft 43 in one direction or the other. A square nut is preferably employed for this purpose and a wrench 46 is employed for rotating the nut. This wrench has formed in the handle thereof an opening 47 which is engageable over the hasp 48 carried by the plate 41, while the jaws 49 of the wrench are engaged with the nut. A padlock 50 may then be applied to the hasp and will hold the wrench against movement and accordingly prevent rotation of the nut and any adjustment of the shaft 43 until unlocked by an authorized person. In order that the bearings, nut and wrench may be protected from the weather, a hood 51 is provided having a slot 52 receiving the 100 hasp and having portions 53 extending over such bearings, nut and wrench to shield the same from the weather.

In the operation of either of the head gates above described, the proportion of 105 water passing through the gate is not subject to change due to changes in the level of the water in the ditch as is the case where the gate is vertically movable and provides a horizontal opening, the vertical height of 110 which is altered. In such cases, it will be obvious that any change in the level of the ditch changes the head to which the opening is subjected and with such change of head or amount of water which will pass through the opening in a given time will vary. As previously stated, the flange 29 serves to deflect particles of floating débris and prevent their lodgment against the walls at the edge of the opening so that they will not interfere with the movement of the gate. This is further assisted by having the interior wall of the duct 12 and the wall 14 meet in a right angle so that there is nothing provided against which such débris may lodge. The 115 groove 16 being opened at both ends is cleansed by the movement of the water and accordingly collection of silt and the like therein which will interfere with the proper 120 movement of the gate is prevented.

It will be obvious that the structure hereinbefore set forth is capable of a certain range of change and modification without in any manner departing from the spirit of my invention and I accordingly do not limit myself to such specific structure except as hereinafter claimed.

I claim:

1. In a head gate for irrigation ditches and the like and as means for delivering a predetermined quantity of water from a main ditch end to a lateral, a duct connecting the main ditch and lateral and communicating with each thereof, a duct at the main ditch thereof being provided at its downstream end with a wall forming one wall of the ditch, a baffle connected at one end of said wall and extending transversely of the ditch and having its upper end level with the surface of the bottom of the duct and its lower surface embedded in the bottom of the ditch, the opposite end of said baffle being provided with a vertical extension forming a portion of the wall of the ditch in opposition to the downstream wall of the duct, a gate for controlling the passage of fluid through the duct, said gate being horizontally movable and being provided at its downstream edge with an outstanding flange deflecting floating débris to the center of the ditch, the main ditch end of the duct having a ledge provided in its upper surface with a groove in which said gate operates, the ledge supporting the gate, said groove having its opposite ends opened.

2. In a head gate for irrigation ditches

and the like and as means for delivering a predetermined quantity of water from a

main ditch end to a lateral, a duct connect-

ing the main ditch and lateral and com-

municating with each thereof, a duct at the

main ditch thereof being provided at its

downstream end with a wall forming one

wall of the ditch, a baffle connected at one

end of said wall and extending transver-

ely of the ditch and having its upper end

level with the surface of the bottom of the

duct and its lower surface embedded in the

bottom of the ditch, the opposite end of said

baffle being provided with a vertical exten-

sion forming a portion of the wall of the

ditch in opposition to the downstream wall

of the duct, a gate for controlling the pas-

sage of fluid through the duct, said gate

being horizontally movable and being pro-

vided at its downstream edge with an out-

standing flange deflecting floating débris to

the center of the ditch, the main ditch end

of the duct having a ledge provided in its

upper surface with a groove in which said

gate operates, the ledge supporting the gate.

3. In a head gate for irrigation ditches

and the like and as means for delivering a

predetermined quantity of water from a

main ditch end to a lateral, a duct connect-

ing the main ditch and lateral and com-

municating with each thereof, a duct at the

main ditch thereof being provided at its

downstream end with a wall forming one

wall of the ditch, a baffle connected at one end of said wall and extending transverse-
ly of the ditch and having its upper end level with the surface of the bottom of the
duct and its lower surface embedded in the
bottom of the ditch, the opposite end of said
baffle being provided with a vertical ex-
tension forming a portion of the wall of the
ditch in opposition to the downstream
wall of the duct, a gate for controlling the
passage of fluid through the duct, said gate
being horizontally movable and being pro-
vided at its downstream edge with an out-
standing flange deflecting floating débris to
the center of the ditch, the main ditch end
of the duct having a ledge provided in its
upper surface with a groove in which said
gate operates, the ledge supporting the gate,
said groove having its opposite ends opened.

4. In a head gate for irrigation ditches

and the like and as means for delivering a

predetermined quantity of water from a

main ditch end to a lateral, a duct connect-

ing the main ditch and lateral and com-

municating with each thereof, a duct at the

main ditch thereof being provided at its

downstream end with a wall forming one

wall of the ditch, a baffle connected at one

end of said wall and extending transver-

ely of the ditch and having its upper end

level with the surface of the bottom of the

duct and its lower surface embedded in the

bottom of the ditch, the opposite end of said

baffle being provided with a vertical exten-

sion forming a portion of the wall of the

ditch in opposition to the downstream wall

of the duct, a gate for controlling the pas-

sage of fluid through the duct, said gate

being horizontally movable and being pro-

vided at its downstream edge with an out-

standing flange deflecting floating débris to

the center of the ditch, the main ditch end

of the duct having a ledge provided in its

upper surface with a groove in which said

gate operates, the ledge supporting the gate,

the upper end wall of the main ditch end

of the duct having members secured thereto

provided with a vertical flange opposing the

main ditch end of the duct and combining

therewith to form a groove receiving the

upper edge of the gate.

5. A head gate for irrigation ditches and

the like, a duct having at one side thereof

a wall, the upper and lower ends of the

wall being provided with opposed grooves

receiving the upper and lower edges of a

horizontally sliding gate and means for con-

trolling the motion of the gate comprising

a horizontally shiftable threaded shaft,

spaced bearings for the shaft, a member

threaded upon the shaft between the bear-

ings, an arm upon the shaft engaging the

gate and common means for rotating the

member or for locking the member to pre-

6. A head gate for irrigation ditches and the like, a duct having at one side thereof a wall, the upper and lower ends of the wall being provided with opposed grooves receiving the upper and lower edges of a horizontally sliding gate and means for controlling the motion of the gate comprising a horizontally shiftable threaded shaft, spaced bearings for the shaft, a member threaded upon the shaft between the bearings, an arm upon the shaft engaging the gate, common means for rotating the member or for locking the member to prevent rotation thereof, comprising a wrench engaging said member and having an opening in the handle thereof and a fixed support having a hasp extendible through the opening of the wrench while the wrench is engaged with the member, the hasp being adapted for the reception of a lock.

7. A head gate for irrigation ditches and the like, a duct having at one side thereof a wall, the upper and lower ends of the wall being provided with opposed grooves receiving the upper and lower edges of a horizontally sliding gate and means for controlling the motion of the gate comprising a horizontally shiftable threaded shaft, spaced bearings for the shaft, a member threaded upon the shaft between the bearings, an arm upon the shaft engaging the gate, common means for rotating the member or for locking the member to prevent rotation thereof, comprising a wrench engaging said member and having an opening in the handle thereof, a fixed support having a hasp extendible through the opening of the wrench while the wrench is engaged with the member, the hasp being adapted for the reception of a lock, and a hood for said bearings, shaft, and wrench

having a slot engageable with the hasp and maintained in its protecting position by the application of the lock.

8. In a head gate for irrigation ditches and the like and as means for delivering a predetermined quantity of water from a main ditch to a lateral, a duct connecting the main ditch and lateral and communicating with each thereof, the duct at the main ditch end thereof being provided at its downstream end with a wall forming one wall of the ditch, a baffle connected at one end of said wall and extending transversely of the ditch and having its upper end level with the surface of the bottom of the duct and its lower surface embedded in the bottom of the ditch, the opposite end of said baffle being provided with a vertical extension forming a portion of the wall of the ditch in opposition to the downstream wall of the duct, a gate for controlling the passage of fluid through the duct, said gate being horizontally movable and being provided at its downstream edge with an outstanding flange deflecting floating débris to the center of the ditch, the main ditch end of the duct having a ledge provided in its upper surface with a groove in which said gate operates, the ledge supporting the gate, the upper end wall of the main ditch end of the duct having a member secured thereto provided with a vertical flange opposing the main ditch end of the duct and combining therewith to form a groove receiving the upper edge of the gate, and means mounted upon said member and the flange thereof controlling the motion of the gate.

In testimony whereof I hereunto affix my signature.

ROBERT E. BOULTON.
